Primary Examiner — S. Bryan Reinholdt, Jr.*Assistant Examiner* — Julia S Folkart(57) **CLAIM**

The ornamental design for a reading pillow, as shown and described.

DESCRIPTION

FIG. 1 is a front, top and right side perspective view of a reading pillow, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dot-dash-dot broken lines in the drawings illustrate portions of the reading pillow, which form no part of the claimed design.

The evenly spaced broken lines representing stitching are part of the claimed design.

1 Claim, 7 Drawing Sheets(56)
